(57) **CLAIM**

The ornamental design for a holder for battery charger, as shown and described.

DESCRIPTION

FIG. 1 is a perspective view of the holder for battery charger showing my new design;

FIG. 2 is a perspective view thereof from another angle;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines shown in the drawings are for the purpose of illustrating portions of the holder for battery charger that form no part of the claimed design.
